UNITED STATES PATENT OFFICE.

WILLIS J. PERKINS AND CARL H. BLOMSTROM, OF GRAND RAPIDS, MICHIGAN;
SAID BLOMSTROM ASSIGNOR TO SAID PERKINS.

ELECTRIC IGNITER FOR EXPLOSIVE-ENGINES.

SPECIFICATION forming part of Letters Patent No. 643,002, dated February 6, 1900.

Application filed December 9, 1897. Serial No. 661,285. (No model.)

To all whom it may concern:

Be it known that we, WILLIS J. PERKINS and CARL H. BLOMSTROM, citizens of the United States, residing at the city of Grand Rapids, 5 in the county of Kent and State of Michigan, have invented certain new and useful Improvements in Explosive-Engines, of which the following is a specification.

This invention relates to explosive-gas engines, and has for its object to provide new and improved spark-producing mechanism which is adjustable to effect the explosions at different periods or positions of the piston and which is simple in construction and will obtain the desired result effectively and certainly. This object is accomplished in the manner and by the means hereinafter described and claimed, reference being made to the accompanying drawings, in which—

Figure 1 is a side elevation of an explosive-engine constructed in accordance with our invention, with parts cut away for the purpose of showing the internal arrangement of the mechanism in detail. Figs. 2, 3, and 4 show 25 detailed views of the spark-producing device. Fig. 5 shows an end elevation of the engine, partially in section. Fig. 6 is a sectional view through the igniter-actuating rod and spark-shifting mechanism. Fig. 7 is a cross-section 30 of the igniter-actuating rod. Fig. 8 is a cross-section of the key which locks the igniter-actuating rod with a sleeve adapted to be oscillated to shift or alter the period of ignition. Fig. 9 is a sectional view through the upper 35 end of the cylinder and head, showing the position of the electrodes and their connections.

Like letters refer to like parts in the drawings.

A represents the cylinder, which is preferably formed integral with the base of the engine, in which the engine-crank moves, the space for the crank-shaft and crank forming an air-tight chamber into which the explosive charge is received, compressed, and retained 45 prior to its admission into the exploding-chamber at the opposite end of the piston. The cylinder-head D is bolted to the upper end of the cylinder A, as shown in Figs. 1 and 5. The crank-chamber has two flanges, 50 one at either side. (Shown by E and F in Fig. 1.) The crank-shaft C is constructed and

operated in the usual manner. The outer case I is preferably made of thin material, such as sheet metal; but any suitable material may be used. In order to procure the best results in vaporizing the inflowing gasoline, dry warm air of substantially unvarying temperature should be used instead of damp cold air of varying temperature. The air takes the course shown by the arrows I², I³, and I⁴, being over the heated surface of the cylinder-head and around the heated cylinder-wall, thereby imparting ample and uniform heat to the air to secure the required result. The space also forms a sort of muffling device to smother the noise of the inlet-valves.

K is a cap covering the upper end of the cylinder A, it preferably being detachably secured by a screw-thread, so as to be readily removed in order to get access to the electrode M of the igniter.

J is also a cap or cover, having a peripheral flange extending downwardly, as shown in Figs. 1 and 5, so as to lap over the outer shell or case I of the cylinder and to leave an air-space for inflowing air to pass through.

We have provided a movable and a stationary electrode, as is usually done where electricity is used to explode the compressed charge. The movable electrode is preferably 80 uninsulated, while the stationary electrode (shown by M) is insulated by any suitable material.

L is the movable electrode and has a bearing in the sleeve L'. This sleeve is preferably 85 tapering at its inner wall of the cylinder. Near its outer end there is a shoulder L², which serves as an abutting surface against which the nut L³ abuts. The nut L³ engages with a screw-thread in the outer wall of the cylinder A and forms a guide and support for the electrode and sleeve L'. The nut L³ is extended into a sleeve and not only engages with the cylinder A by a screw-thread, but it also has a lock-nut L⁴ for retaining it securely 95 in place. The sleeve L' is surrounded with water, (see Fig. 9,) which circulates in the water-space, thereby preventing the spindle of the movable electrode from heating, thus enabling the operator to keep the spindle at 100 all times lubricated and in good order. An oil-duct L⁵ is provided to receive oil for the

purpose of lubricating the journal of the electrode L, and a spring-seated puppet-valve L⁶ prevents the charge from escaping from the ignition-chamber, but permits the oil to flow freely to the inner journal through oil-duct L⁵ when valve L⁶ is pressed down by the end of the oil-can spout. For the purpose of securing a quick break to produce an efficient spark we provide a projecting contact-arm L⁷ on one end of the electrode L, and on the other end of L we provide two arms. One of these arms (shown by L⁸) is keyed or otherwise rigidly connected to the electrode L, while the other arm (shown by L⁹) has an oscillating motion and is raised by the contact-point of the spark-actuating rod. A spring L¹⁰ is shown in Fig. 2. The form of the movable arm is shown clearly in Fig. 3, and the form of the arm which is keyed to the electrode is shown in Fig. 4. The arm L⁸ extends beyond the arm L⁹ and forms the contact-point for a dog on the actuating-rod N. The rod N is moved by an eccentric, as hereinafter described, and contributes a vertical vibratory motion to two contact-points. One is shown by N⁴ and the other by N⁹. When the actuating-rod N is moved upward, one of the contact-points (N⁴, as shown in Fig. 5,) comes in contact with the free end of arm L⁸, which arm being attached to the electrode L, as above described, turns the electrode-arm L until the electrodes are in contact, and the continuous upward movement of actuating-rod N continues the contact of the electrodes under increasing spring-pressure until the free end of the spring-arm L⁸ escapes from the point N⁴, when the spring L¹⁰ carries the free end of the arm L⁸ down, giving a quick blow or stroke on the arm L⁹, which is rigid with L, oscillating or rocking the same a sufficient distance to separate the electrodes and producing a most efficient spark for igniting the gas in the compression-chamber. Thus the electrodes are brought together by a comparatively slow motion, are held together by an increasing pressure, and are separated by a quick stroke. The spring L¹⁰ may be of any suitable form to enable the described action to be secured between the two arms L⁸ and L⁹. It will be noted that this arrangement of parts eliminates all friction on electrode L, as there is no outside tension applied thereto. The actuating-rod N is operated by an eccentric preferably, although other mechanism would give substantially the same movement to it. The lower end of the actuating-rod N fits in a suitable socket N', formed in a projection of the eccentric-strap N², which eccentric-strap is actuated by an eccentric on the crank-shaft G. Toward the upper end of the actuating-rod N said rod has a sliding bearing pivoted at right angles to the rod N, the pivot being shown in Figs. 1 and 5 by N³. The pivot N³ is supported in journal-box on arm N¹⁹, which is preferably fastened to the cylinder. The bearing or sleeve is rocked or oscillated by movement of the actuating-rod N as it is moved by the

eccentric, causing the upper end of the actuating-rod to describe an ellipse, the major axis of which in the example of our invention would be the throw of the eccentric, while the minor axis would depend upon the relative position of the pivoted bearing upon the actuating-rod to the dogs N⁴ and N⁹. If, however, the pivoted bearing be placed nearer the lower end than the upper end of the actuating-rod, then the major axis would be horizontal and the throw of the eccentric would be the minor axis. By changing the position of this pivoted bearing the movement of the upper end of the actuating-rod may be varied at pleasure. Any suitable battery, as O, may be used. Attached to coil P are wires O' and P', with binding-posts and electrode-points M and L⁷. 85

In the example of our invention shown in Fig. 6 there are two contact-points N⁴ and N⁹, both being on the same sleeve and rigidly secured to the actuating-rod, but adjustable longitudinally upon the actuating-rod by means of the two nuts shown in said Fig. 6. The lower contact-point N⁹ is used when the engine is first started in order that the combustion may take place as the crank passes over the center and not cause the motion of the cranks to reverse by the too-sudden ignition and explosion of the charge. The upper point of contact N⁴ is used after the engine is under motion, for the reason that it is desirable that complete combustion of the charge should take place in the almost-immeasurable space of time allowed therefor, the motion of the rapidly-moving balance-wheel acting to carry the crank over the center. The early ignition or ignition before the crank on the crank-shaft passes the center gives increased power and speed to the engine and economizes the gas or gasoline used. The actuating-rod N has a seat in the eccentric N² and is held in vertical position by means of a spring N⁸, which spring bears against a collar N⁷, which is securely fastened to the screw-threaded sleeve N⁶, a second collar being attached to the actuating-rod, as shown by N⁵. In case of a premature explosion reversing the engine the contact-point N⁴ or N⁹ would engage with the arm L⁸, actuating-rod N being held up thereby, while the spring N⁸ would yield. The actuating-rod N is provided with a slot N¹⁰, through which slot passes the key N¹⁴, having its outer ends supported by the sleeve N¹¹, which sleeve N¹¹ has a free rotary movement within the sleeve N³, already described. The upper end of the sleeve N¹¹ is provided with a screw-collar N²⁰, which abuts against the upper end of collar N³, and its lower end is enlarged so as to form a bearing at that end against the lower end of sleeve N³, as fully shown in Fig. 6. The sleeve N¹¹ has also a projection to which is pivoted the handle N¹². The handle N¹² has a lug N²¹, which is adapted to engage with two or more slots at N²⁰ in sleeve N³. When the handle is in the position shown by solid lines in Fig. 6, the lug

N^{21} will be in engagement with slot N^{26} . By lowering the handle to the position shown by dotted lines the lug is disengaged and the sleeve N^{11} encircles the rod N , thereby changing the contact-points N^4 and N^9 at pleasure.

R' , Fig. 5, is the water-inlet pipe through which the water is forced into the water-space B between the cylinder and the shell surrounding the same. The water passes upward till it reaches the point R^2 in the cylinder-head, from whence it flows downwardly through the pipe R^3 and escapes through the outlet-pipe R^5 . The pipe R^3 is screw-threaded into the base of the water reservoir, and R^4 is a hole drilled to receive the lower end of R^5 and connecting R^3 and R^4 . By drilling a small hole R^6 a small stream of water will flow into the exhaust-pipe S , thereby keeping down the temperature of the exhaust-pipe. A plug R^7 is used to close the hole R^6 and to prevent the escape of the water except into the exhaust-pipe. It also furnishes means of obtaining easy access to the hole R^6 , so as to clean the same and prevent clogging. The exhaust-pipe S is carried down inside of the outer shell or zone Q and is provided with an elbow S' , securely fastened to it by a single bolt S^2 , thereby permitting the elbow S' to be moved in any required direction without affecting the joint. This elbow is also easily removed and replaced from the engine. Into the end of the elbow S' is screwed the end of the exhaust-pipe S^6 . A prolongation of the exhaust-gas duct S is provided with a relief-cock screwed therein, having its inner end beveled and fitted into an inlet-hole which opens into the cylinder. By unscrewing the relief-cock S^4 the imprisoned charge will escape through the exhaust until the piston passes above the part S^4 , when the compression will ensue.

Having thus described our invention, what we claim to have invented, and desire to secure by Letters Patent, is—

45 1. In a gas-engine, the combination with a cylinder having an inner and an outer wall with a water-space therebetween, of a movable electrode, a bearing therefor exposed to the water in said space, and means closing the opening into the jacket through which the said bearing passes, substantially as specified.

2. The combination with a cylinder having an inner and an outer wall with water-space therebetween, of a movable electrode, a sleeve in which it has a bearing, and which is exposed to the water in said space, and a nut engaged with a screw-thread in the outer wall and closing the opening into the jacket through which the said sleeve passes, substantially as specified.

3. In a gas-engine, the combination of a cylinder having an inner and outer wall with water-space therebetween the stationary and movable electrode adapted to have contact with each other in the ignition-chamber, a sleeve encircling the movable electrode and

passed through said water-space, an opening through the cylinder-head, an oil-duct adapted to convey oil to the movable-electrode journal, and a puppet-valve adapted to close said passage, substantially as described.

4. The combination in a gas-engine, of a movable and a stationary electrode, said movable electrode suitably journaled and extending from the outside to the inside of the cylinder and passed through a water-space, an opening extending through the cylinder-head adapted to convey oil to the movable-electrode journal, and a valve adapted to be depressed for the purpose of admitting oil to the journal of said electrode, substantially as described.

5. The combination in a gas-engine, of a movable electrode, a reciprocating rod to actuate the movable electrode, a sleeve encircling said reciprocating rod at some point between its two ends, two actuating-tappets carried by the upper end of the rod, a pivotal journal-box supporting said sleeve, and a key for holding the said sleeve and rod in relative rotary adjustment, but permitting of longitudinal movement of said rod with reference to said sleeve, substantially as described.

6. In a gas-engine, the combination of a movable electrode, a reciprocating bar or rod eccentrically attached to the crank-shaft at one end and free at the other end and supported between its ends in a pivoted bearing in which it slides, its free end adapted to intermittently engage with and move the electrode, substantially as described.

7. In a gas-engine, the combination of a movable electrode, a reciprocating actuating-rod, a sleeve encircling the said reciprocating rod, a pivotal journal-box supporting the said sleeve, a key for holding said sleeve in relative position, two actuating-tappets carried by the upper end of the rod and suitable means for mechanically revolving the rod within the pivotal sleeve, substantially as described.

8. The combination in a gas-engine with a movable and a stationary electrode, of a reciprocating rod for actuating the electrodes eccentrically attached to the crank-shaft, a pivoted central support for the said rod in which it slides and adapted to give to the upper end or contact-point of said rod an elliptical path, substantially as described.

9. The combination in a gas-engine with a movable and stationary electrode, said movable electrode journaled in a sleeve situated in the cylinder-walls, a cylinder-head covering one end of said cylinder and surrounded by a water-space, a puppet-valve closing the oil-duct to the movable electrode, and a valve-seat adapted to be depressed for admitting the oil to the journal of said electrode, substantially as described.

10. The combination in an explosive-engine having a movable and a stationary electrode, a contact dog or lug on the movable electrode, a reciprocating rod having a plurality of

tappets adapted to engage the said tappets on the movable electrode, said reciprocating rod being eccentrically attached to the crank-shaft, a central support for the said rod adapted to give to the upper end or contact-point of said rod a substantially oval path.

11. The combination with an explosive-engine, having a movable and a stationary electrode, of dogs or contact-points on said movable electrode, and a reciprocating rod having a plurality of adjustable tappets adapted to engage at predetermined times with said

dogs or lugs on the movable electrode, said reciprocating rod being eccentrically connected to the crank-shaft, substantially as described.

In witness whereof we have hereunto set our hands and seals in the presence of two witnesses.
